US0D1029952S

(12) **United States Design Patent** (10) **Patent No.:** **US D1,029,952 S**
(45) **Date of Patent:** **** Jun. 4, 2024**

(54) **TOY GRABBING DEVICE**

(71) Applicant: **LI HSEN PLASTICS CO., LTD.**,
New Taipei (TW)

(72) Inventor: **San-Lang Chiang**, New Taipei (TW)

(73) Assignee: **LI HSEN PLASTICS CO., LTD.**,
New Taipei (TW)

(**) Term: **15 Years**

(21) Appl. No.: **29/802,787**

(22) Filed: **Aug. 9, 2021**

Related U.S. Application Data

(60) Division of application No. 16/881,014, filed on May 22, 2020, now abandoned, which is a continuation-in-part of application No. 16/280,056, filed on Feb. 20, 2019, now abandoned.

(57) **CLAIM**

The ornamental design for a toy grabbing device, as shown and described.

DESCRIPTION

FIG. 1 is a perspective view of a toy grabbing device showing my new design;

FIG. 2 is a front elevational view thereof;

FIG. 3 is a rear elevational view thereof;

FIG. 4 is a left side view thereof;

FIG. 5 is a right side view thereof;

FIG. 6 is an enlarged top plan view thereof;

FIG. 7 is an enlarged bottom view thereof; and,

FIG. 8 is a cross-sectional view thereof taken at line **8-8** in FIG. 6.

The dot-dash broken line arrows in FIGS. 6 and 8 are used to identify the cross-section view and are for reference purposes only, and the broken lines in FIG. 8 illustrate portions of the article that form no part of the claimed design.

1 Claim, 8 Drawing Sheets
